ABSTRACT OF THE DISCLOSURE

The use of compounds of the formula:

wherein R and R¹ are each alkylene having 1 to 7 carbon atoms and X is lower alkylsulfonyl, for the control of amebiasis is described.

BACKGROUND OF THE INVENTION

This invention relates to the use of various 1-alkylsulfonylalkyl - 2 - alkyl - 5 - nitroimidazoles in controlling amebiasis.

Amebiasis is the generic term given to an infectious parasitic disease caused by *Entameba histolytica*. The disease causes inflammation of the colon, characterized in some cases by the passage of bloody stools. The mild form of the disease, usually occurring in the temperate climates, is usually characterized by ill-defined gastrointestinal complaints, diarrhea, constipation, fatigue, and in some cases abdominal discomfort. In the tropics the disease takes a more severe course (amebic dysentery) and is manifested by the daily passage of numerous fluid or semi-fluid stools, usually containing enormous numbers of active trophozoites. This acute stage of the disease is very debilitating with the patient becoming emaciated and anemic.

A serious complication which may occur in the advanced stages of the disease is the possible involvement of the liver by intestinal infection giving rise to amebic hepatitis and the formation of amebic abscesses.

The therapeutic objective is the elimination of all amebae from the affected tissues, the exact mode of treatment depending upon the severity of the infection. Two widely used drugs in treating the disease are emetine and Resotren.

We have now found that the compounds described in the present invention are effective against amebiasis.

SUMMARY OF THE INVENTION

The present invention provides a method for combating amebiasis in a human host comprising orally administering to the infected patient an amebicidal amount of a compound having the formula:

2

where R and R¹ are each alkylene having from 1 to 7 carbon atoms and X is lower alkylsulfonyl; and their pharmaceutically-acceptable acid addition salts.

The invention also provides an amebicidal composition comprising a compound having the herein above mentioned formula and a pharmaceutically acceptable carrier.

DETAILED DESCRIPTION OF THE INVENTION

10 We have now found that various 1-alkylsulfonylalkyl-2-alkyl-5-nitroimidazoles are effective in controlling amebiasis. These compounds have previously been described in U.S. Patent 3,376,311. Besides the methods of preparation given there, another synthetic scheme that 15 can be used for the preparation of these compounds is given below:

R¹=alkylene having 1 to 7 carbon atoms
X=lower alkylsulfonyl

40 In the above procedure the appropriate 2-alkyl-5-nitroimidazole and β -bromo-ethyl alkyl sulfide is reacted in formic acid to give the corresponding alkyl-[2-(2-alkyl-5-nitro-1-imidazolyl)ethyl]sulfide, which is then converted to the tosylate salt. Oxidation of the tosylate salt 45 with NaOCl in chloroform affords the desired alkyl[2-(2-alkyl-5-nitro-1-imidazolyl)ethyl] sulfone.

The necessary β -bromoethyl alkyl sulfides are conveniently prepared by reacting ethyl mercaptan, bromine, and ethylene in carbon tetrachloride at low temperatures.

50 In view of the fact that the compounds of this invention are basic in nature, they will form water-soluble salts with the appropriate acids. Although such salts must be pharmaceutically acceptable, since the final products are intended for animal and human consumption, it is 55 possible to convert the desired compound to a pharmaceutically unacceptable salt and subsequently convert the latter salt to the free organic compound by treatment with a base; the imidazole so obtained is then converted to a pharmaceutically acceptable acid addition salt there-60 of in the manner hereinafter indicated.

For instance, the acid addition salts of the compounds of this invention can be prepared by treating free base with a substantially equivalent amount of the chosen acid in an aqueous solution or in a suitable organic solvent 65 such as methanol or ethanol. Upon careful evaporation of the solvent, the solid salt is obtained. Alternatively,

other recovery techniques are also applicable, such as freeze-drying when the solvent is water or the use of an anti-solvent in the case of an organic solution, e.g., the addition of diethyl ether to an ethanolic solution of the product will cause precipitation of the desired product to occur.

The acids which are used to prepare the pharmaceutically acceptable acid addition salts of this invention must, of course, be those which necessarily form non-toxic acid addition salts containing a pharmaceutically acceptable anion, such as the hydrochloride, hydrobromide, hydriodide, nitrate, sulfate or bisulfate, phosphate or acid phosphate, acetate, lactate, citrate or acid citrate, tartrate or bitartrate, oxalate, succinate, maleate, glutonate, saccharate, methanesulfonate, ethanesulfonate, benzenesulfonate and p-toluenesulfonate salts, etc.

In the treatment of amebiasis, it is generally preferred to administer the compounds of the present invention orally. The compounds are usually administered at a dosage level of from 0.300 g. to 3.00 g. per day. The exact amount will depend upon the amebicidal activity of the particular compound chosen. A preferred regimen is to administer 0.100 to 1.00 grams of compound three times a day.

Nevertheless, it is to be appreciated that still other variations may also occur in this respect, depending upon the individual response to said medicament, as well as on the particular type of pharmaceutical formulation chosen and the time period and interval at which such administration is carried out. In some instances, dosage levels below the lower limit of the aforesaid range may be more than adequate, while in other cases still larger dosages may be employed without causing any harmful or deleterious side effects to occur provided that such higher dose levels are first divided into several smaller doses that are to be administered throughout the day.

For purposes of oral administration, tablets containing various excipients such as sodium citrate, calcium carbonate and dicalcium phosphate may be employed along with various disintegrants such as starch and preferably potato or tapioca starch, alginic acid and certain complex silicates, together with binding agents such as polyvinyl-pyrrolidone, sucrose, gelatin and acacia. Additionally, lubricating agents such as magnesium stearate, sodium lauryl sulfate and talc are often very useful for tabletting purposes. Solid compositions of a similar type may also be employed as fillers in soft elastic and hard-filled gelatin capsules; preferred materials in this connection also include lactose or milk sugar as well as high molecular weight polyethylene glycols. When aqueous suspension and/or elixirs are desired for oral administration, the essential active ingredient may be combined with various sweetening or flavoring agents, coloring matter or dyes and, if so desired, emulsifying and/or suspending agents, together with such diluents as water, ethanol, propylene glycol, glycerin and various like combinations thereof.

Although the preferred mode of administration of the herein described compounds is oral, they may be administered parenterally as well.

For purposes of parenteral administration, solutions of these particular compounds in sesame or peanut oil or in aqueous-propylene glycol may be employed, as well as sterile aqueous solutions of the corresponding water-soluble acid addition salts previously enumerated. Such aqueous solutions should be suitably buffered if necessary and the liquid diluent rendered isotonic with sufficient saline or glucose. These particular aqueous solutions are especially suitable for intravenous, intramuscular and subcutaneous injection purposes. In this connection, the sterile aqueous media employed are readily obtained by standard techniques well known to those skilled in the art. For instance, distilled water is ordinarily used as the liquid diluent and the final preparation is passed through a suitable bacterial filter, such as a sintered-glass filter or a diatomaceous-earth or unglazed porcelain filter. Preferred filters of this type include the Berkefeld, the

Chamberland and the asbestos disc-metal Seitz filter, wherein the fluid is sucked through the filter candle into a sterile container with the aid of a suction pump. Needless to say, the necessary step should be taken throughout the preparation of these injectable solutions to ensure that the final products are obtained in a sterile condition.

(I) Preparation of Starting Materials

(A) Preparation of 2-alkyl-5-nitroimidazoles

To 300 ml. of 98% H_2SO_4 was added 136 g. (1.66 moles) of 2-methylimidazole, allowing the temperature to rise to 132°. To this hot solution was added a total of 240 ml. of 70% HNO_3 at such a rate as to maintain a reaction temperature of 150-170°. After the addition of HNO_3 was completed the mixture was stirred for 1.5 hours at ambient temperature, cooled and poured over ice. The pH was adjusted to 6.0, and the product collected by filtration to yield 305 g. (45.2% of theory) of 2-methyl-5-nitroimidazole; M.P. 250-252°.

Using the above procedure and the appropriately substituted 2-alkyl-imidazoles the following 2-alkyl-5-nitroimidazoles are similarly prepared:

2-n-heptyl-5-nitroimidazole
2-n-butyl-5-nitroimidazole
2-i-propyl-5-nitroimidazole
2-n-pentyl-5-nitroimidazole

(B) Preparation of β -bromoethyl alkyl sulfides

To a solution of 400 ml. of CCl_4 and 141 g. (2.27 moles) of ethyl mercaptan which was cooled to -16° was added 359 g. (2.27 moles) of Br_2 in 360 ml. CCl_4 so that the temperature of the mixture did not exceed -10°. The resulting mixture was sparged for 20 hours with N_2 then cooled again to -14°. Next 81.2 g. (2.9 moles) of ethylene was added, maintaining a temperature of 0° or less. After the ethylene had been added the reaction was left at ambient temperature for 20 hours, the solvent stripped and the residue distilled to yield 239 g. of β -bromoethyl ethyl sulfide (62.5% of theory), B.P. 68° (18 mm.).

Using the appropriate alkyl mercaptans, the following β -bromoethyl alkyl sulfides are also prepared:

β -bromoethyl-n-propyl sulfide
 β -bromoethyl-n-methyl sulfide
 β -bromoethyl-i-propyl sulfide
 β -bromoethyl-n-butyl sulfide
 β -bromoethyl-n-pentyl sulfide
 β -bromoethyl-i-butyl sulfide

(II) Preparation of 1-alkylsulfonylalkyl-2-alkyl-5-nitroimidazoles

(A) Preparation of ethyl[2-(2-ethyl-5-nitro-1-imidazolyl)ethyl]sulfide tosylate

A solution of 178 ml. of CH_3COOH and 250 g. (1.96 mole) of 2-methyl-2-nitroimidazole was heated to 90°. Then 166 g. (0.98 mole) of β -bromoethyl ethyl sulfide was added and the mixture held at 90° for 1.5 hours. The CH_3COOH was removed at reduced pressure, and the residue quenched in 260 ml. of water. The unreacted 2-methyl-5-nitroimidazole was removed by filtration, and the pH of the aqueous phase adjusted to 7.0. The product was extracted with $CHCl_3$, which after drying and concentration gave 166 g. of an oil. The oil was extracted with ether and the extract concentrated to yield 130.7 g. of product still contaminated with the 4-nitro isomer. The mixture was dissolved in 120 ml. ethyl acetate and added to 556 g. of p-toluenesulfonic acid in 200 ml. ethyl acetate. On cooling to -2°, ethyl[2-(2-methyl-5-nitro-1-imidazolyl)ethyl]sulfide tosylate precipitated and was collected to yield 126 g. (33% of theory), M.P. 112-114°.

(B) Preparation of ethyl[2-(2-methyl-5-nitro-1-imidazolyl)ethyl]sulfone

A mixture of 530 ml. of H_2O , 126 g. (0.326 mole) of

tosylate salt from the preceding procedure A above and 200 ml. CHCl_3 was cooled to 7° , and 126 ml. of 12.5% NaOCl was added in one portion. The resulting mixture was stirred for 15 minutes, then extracted with CHCl_3 . The combined extracts were washed with saturated NaHCO_3 , and the CHCl_3 replaced with isopropyl alcohol. The solids were collected and dried to yield 39 g. (48% of theory), M.P. 125-126°.

The 2-alkyl-5-nitroimidazoles in Part I-A are reacted with the β -bromo-ethyl alkyl sulfides in Part I-B according to the procedure of Part II-A, and the resulting tosylates are then converted to the sulfones according to the procedure of Part II-B.

(III) PREPARATION OF THE ACID ADDITION SALTS OF THE 1-ALKYLSULFONYLALKYL-2-ALKYL-5-NITROIMIDAZOLES

The 5-nitroimidazole compounds described herein are converted to their acid addition salts by the following general procedure.

To a methanolic solution containing 0.10 mole of the 5-nitroimidazole is added 0.1 mole of a suitable acid. The solvent is removed by evaporation under reduced pressure or lyophilization and the solid acid addition salt is filtered and dried. Among the acids that can be used in this procedure are hydrochloric acid, acetic acid, sulfuric acid, citric acid and oxalic salt. Other suitable solvents are ethanol, water, and mixtures thereof.

The following examples are provided to illustrate more fully the scope of the present invention; however, they should not be construed to be limitations thereof.

EXAMPLE I

The compounds of the present invention are effective in the treatment and control of amebiasis. Table I below contains test results showing the efficacy of a typical compound with rats infected with *Entamoeba histolytica*, the causative agent of human amebiasis. These tests were conducted as follows:

Laparotomies were performed on 35-45 gram, male, albino rats in order to inject approximately 200,000 *Entamoeba histolytica* trophozoites intracecally. The inoculum was prepared from pooled 48 hour cultures maintained on Locke's egg slant-Locke's overlay medium in the presence of an undetermined flora. The test drug was administered for four consecutive days commencing 48 hours post-infection. The efficacy of the therapy was evaluated 24 hours after the administration of the fourth dose. The percent of the rats (7-12 per group) cleared of infection, the average degree of infection (A.D.I.) and the percent efficiency (A.D.I. of treated group divided by A.D.I. of infected control times 100) were determined. The A.D.I. was determined using the following lesion scoring system: 0=no cecal lesions; 1=few amebae; 2=many amebae, no cecal inflammation; 3=many amebae, cecal inflammation; 4=many amebae, cecal inflammation and/or ulceration and mucous. The minimum effective dose (MED) of the experimental drug was the lowest dose which produced a percent efficiency equal to or greater than 90.

TABLE I

CH₂CH₂SO₂CH₂CH₃

Mg./kg.	No. of rats	Percent cleared	A.D.I.	Percent efficiency
200	10	90	0.10	95
50	10	70	0.30	84
25	6	33	3.00	0
6.25	24	54	1.02	47
3.125	9	33	2.02	0
Infected control	24	33	1.94	0

MED $\leq$ 100 mg./kg.

EXAMPLE II

A tablet base is prepared by blending the following ingredients in the proportions indicated:

Parts

20	Sucrose, U.S.P.	82
	Tapioca starch	14
	Magnesium stearate	4

This base is then blended with sufficient amounts of the 2-nitroimidazoles of the present invention to give after 25 tabletting tablets containing from 100 to 1000 mg. of active ingredient.

Oral administration of these tablets 3 times a day to a human host suffering from amebiasis provides effective control of the disease.

30 What is claimed is:

1. A method for combatting amebiasis in a human which comprises orally administering to said human an amebicidae amount of a compound having the formula:

40 where R and R¹ are each alkylene having 1 to 7 carbon atoms; X is lower alkylsulfonyl and the pharmaceutically acceptable acid addition salts thereof.

45 2. The method of claim 1 wherein said compound is such that R is alkylene having 1 to 7 carbon atoms, X is lower alkylsulfonyl and R¹ is methylene.

3. The method of claim 1 wherein said compound is such that R is ethylene, X is ethylsulfonyl and R¹ is methylene.

50 4. The method of claim 1 wherein said compound is such that R is ethylene, X is propylsulfonyl and R¹ is methylene.

55 5. The method of claim 1 wherein said compound is such that R is ethylene, X is methylsulfonyl and R¹ is methylene.
